UNITED STATES PATENT OFFICE.

EDWARD J. COLBY, OF CHICAGO, ILLINOIS, ASSIGNOR TO THE COLBY IMPROVEMENT COMPANY, OF SAME PLACE.

COIN-CONTROLLED OPERA-GLASS.

SPECIFICATION forming part of Letters Patent No. 434,377, dated August 12, 1890.

Application filed December 10, 1889. Serial No. 333,190. (No model.)

To all whom it may concern:

Be it known that I, EDWARD J. COLBY, a citizen of the United States, and a resident of Chicago, county of Cook, and State of Illinois, have invented a certain new and useful Improvement in Coin-Controlled Opera-Glasses, of which the following is a full, clear, and exact specification.

My invention relates to coin-controlled optical instruments, and has for its object to provide means whereby such instrument may be permanently locked in such manner as not to be in use except when freed by the introduction of a coin. This I accomplish by means of the mechanism shown in the accompanying drawings, wherein—

Figure 1 is an end part sectional view of the device; Fig. 2, a section on the line X X; Fig. 3, a section on the line Y Y.

Like parts are indicated by the same letters in all the figures.

A A are the tubes of an opera-glass; B, the cross-bar; C, the hollow cross-bridge; E E, the apertures of such tubes; F, a bridge or partition within the cross-bridge C.

G is a rod carrying the clutch H at its upper end and pivoted at J in the cross-bridge F. L is a slot in such rod registering with the slot M, and also with the slot M' in the thimble M², within which freely rotates the head M³ on the handle M⁴ or knob M⁵, and also with the slot M⁶ in such head. The head M³ has an annular groove N, into which projects the notched spring-plate N', which lies in the recess N² in the inner surface of the thimble M². A rod O secured to the notch in the spring N' is provided with a lug P, which is engaged by the key R to retract the rod O and thus withdraw the spring N'.

I have devised many kinds of coin-controlled or coin-freed mechanisms to prevent the focusing of the optical instruments; but the form which I here exhibit is that form which has specially been applied to opera-glasses, and hence I have confined the illustration to opera-glasses, though with slight modification. The device or principle thereof could be easily applicable to the control of other instruments.

S is the rod to which the movable or inner portion of the tube is secured, and this rod

is screw-threaded at S' within the sleeve S², which is provided with the thumb-piece S³. The sleeve S² is secured to the outer and principal portion of the tube. Now, as is well known, by turning the thumb-piece in the desired direction the rod S will travel and will be caused to travel or reciprocate within the sleeve S², and thus the lenses of the opera-glass be moved so as to properly focus the same and permit the proper use of the glasses.

T T is a chain attached to the handle or knob so that the glass may be secured in position.

V is the coin.

The use and operation of my invention are as follows: The coin V having been inserted through the slot M and slot M' into the slot M⁶ in the rotating head and the slot L in the rod G, it projects, as shown in Fig. 3, into the groove N. If now the handle or knob be turned, the coin will turn with it, and hence the rod G will also turn. By continuing this motion the rod G will be rotated, say, through ninety degrees, whereupon the clutch H will be disengaged from the teeth on the thumb-piece S³, and the latter will be released and will be free to rotate, so that the lenses may be extended or contracted to permit the free and proper use of the glasses. At the same time the coin V will engage the spring N' and force the same backward into the recess N² until it engages the notch, whereupon the coin will be locked securely in position, and with it all of the rotating parts, and the opera-glass be free for use.

By now inserting the key R and retracting the spring the knob or handle will be free to be moved, together with the coin, from the hollow bridge C. The spring immediately restores the clutch H to the position shown in Fig. 1, where it engages the thumb-piece S³, and the parts are again locked into position. The coin may now be removed from the head and the latter reinserted in its aperture. It will be seen that when thus out of use the opera-glasses are free to rotate upon the handle or knob. The form of the lock could of course be greatly altered, the essential feature, obviously, consisting in the application of means whereby the reciprocating portions of an optical instrument may be locked so as to prevent their

reciprocation to focus the instrument by means of a coin-free mechanism.

Having thus described my invention, what I claim, and desire to secure by Letters Patent, 5 is as follows:

1. The combination of an optical instrument with a focusing-preventing lock and coin-controlled mechanism which governs such lock.
2. The combination of an optical instrument 10 with a movable part adapted to focus the same, a lock to such part, and coin-controlled mechanism to control such lock.
3. The combination of an optical instrument with a reciprocating lense-carrying portion, 15 devices to reciprocate such portion, and coin-controlled mechanism to govern such devices.
4. The combination of an opera-glass hav-

ing two relatively movable portions, one of which moves with the lenses of a lock which prevents them from moving one upon the other, and coin-controlled mechanism to govern such lock.

5. A coin-controlled lock containing a rotating piece normally free to move, a socket in which it can rotate and in which it is normally secured, coin-receiving slots through such socket and rotating piece, and a catch to prevent the rotation after the coin has been introduced and turned a certain distance. 25

EDWARD J. COLBY.
